COMBINED VANITY CHAIR AND HAIR DRYER

Edward J. Petrick, Park Ridge, and Horst Genger, Chicago, Ill., assignors to Belford Manufacturing, Inc., Schiller Park, Ill., a corporation of Illinois

Filed Sept. 14, 1966, Ser. No. 3,853

Term of patent 14 years

(Cl. D15—1)

FIG. 1

FIGURE 1 is a side elevational view of a combined vanity chair and hair dryer embodying the design of this invention, the other side being a mirror image thereof;

The dominant features of our design reside in those portions shown in full lines on the drawing.

We claim:

The ornamental design for a combined vanity chair and hair dryer, as shown and described.
